UNITED STATES PATENT OFFICE.

JOHN E. O'NEILL, OF BRONXVILLE, NEW YORK.

FASTENER.

Application filed August 15, 1922. Serial No. 531,947.

To all whom it may concern:

Be it known that I, JOHN E. O'NEILL, a citizen of the United States, residing at Bronxville, in the county of Westchester 5 and State of New York, have invented certain new and useful Improvements in Fasteners, of which the following is a specification, reference being had therein to the accompanying drawing.

10 My invention relates to improvements in fasteners or attaching means such as may be used for rubber heels or the like, and more particularly has reference to and is illustrated in the accompanying drawing as 15 a pronged device adapted to be driven into the leather heel of a shoe, leaving a clip-like structure projecting therefrom adapted to engage and hold a rubber heel when the same is pressed thereon.

20 Referring to said drawings, Fig. 1 illustrates in perspective, a suitable form of fastener embodying an application of my invention. Fig. 2 is a detail of the heel portion of a shoe partly broken away showing 25 an application of a preferred form of my fastener before the rubber heel has been applied. Fig. 3 is a similar view showing the rubber heel applied, and Fig. 4 is a plan view looking down upon the rubber heel shown in 30 Fig. 3.

5 indicates the body portion of the fastener from which projects several prongs such as 6, and 7—8 indicate the walls of a clip-like structure between which a wire, rod 35 or other fastening means imbedded within the heel may be retained. The heel when formed is provided with openings or holes such as 9 which preferably do not extend entirely through the heel, but which allow 40 for the passage of the clip end of the fastener as shown. The heel is also preferably provided with wires or rods 10 which extend across said holes or openings as shown so as to be in position to be engaged by the clips.

45 In applying the rubber heel, it is first coated or wetted and then placed against the leather heel to show where the openings come and at those points, the fasteners are driven into the leather heel, the prongs holding the same securely in position. The rubber heel may now be applied again in the same position bringing the holes and wires directly over the clips of the fasteners and by striking the rubber or pressing the same 50 upon the clips, a secure union will be effected.

The outer edges of the clip are preferably beveled as indicated at 11 to guide the same conveniently and easily within the holes of the rubber heel, and the inner edges are also 60 preferably beveled as shown at 12 to guide the wire or rod such as 10 to its seat or retaining groove 13 at the base of the clip. The clip is also preferably grooved upon opposite sides as indicated at 14 to provide the 65 necessary resiliency for the passage of the wire or rod when the heel is being driven home, and it will of course be readily understood that once the wires or rods are seated within the grooves or seatings 13 the heel 70 is practically immovable and can only be removed with great effort.

Instead of fastening heels, the fastener may be used for attaching other devices, and instead of four or any other number of 75 prongs, the fastener may be provided with a screw threaded shank or other fastening means. In fact, various modifications may be made in the construction and arrangement of parts without departing from the 80 spirit of the invention as claimed.

I claim:

1. In combination, an integral pronged base and a bifurcated projecting portion, a 85 base into which said pronged portion projects, an attachment having a hole into which said bifurcated portion projects, and a rod projecting laterally through said attachment and said bifurcated portion.

2. In combination, an integral pronged 90 base and a bifurcated projecting portion, a base into which said pronged portion projects, an attachment having a hole into which said bifurcated portion projects, and a rod projecting laterally through said attachment and said bifurcated portion, said bifurcated portion having a seating into which said attachment may be pressed and secured.

3. In combination, an integral pronged 100 base and a bifurcated projecting portion, a base into which said pronged portion projects, an attachment having a hole into which said bifurcated portion projects, and a rod projecting laterally through said attachment and said bifurcated portion, said attachment and rod being adapted to be pressed upon said bifurcated projection.

4. In combination, an integral pronged 110 base and a bifurcated projecting portion, a base into which said pronged portion projects, an attachment having a hole into

which said bifurcated portion projects, and a rod projecting laterally through said attachment and said bifurcated portion, said attachment and rod being adapted to be 5 pressed upon said bifurcated projection, said bifurcated portion remaining in its normal undistended form.

5. In combination, an integral pronged base and a bifurcated projecting portion, a 10 base into which said pronged portion projects, an attachment having a hole into which said bifurcated portion projects, and a rod projecting laterally through said attachment and said bifurcated portion, said 15 bifurcated portion having a seating into which said attachment may be pressed and secured, the walls of said bifurcated portion thinner at the base than at the end.

6. In combination, an integral pronged

base and a bifurcated projecting portion, a 20 base into which said pronged portion projects, an attachment having a hole into which said bifurcated portion projects, and a rod projecting laterally through said attachment and said bifurcated portion and 25 said bifurcated portion adapted to resiliently grip said rod.

7. In combination, an integral pronged base and a bifurcated projecting portion, a 30 base into which said pronged portion projects, an attachment having a hole into which said bifurcated portion projects, and a rod projecting laterally through said attachment and said bifurcated portion, said 35 rod secured in said attachment.

In testimony whereof I hereunto affix my signature.

JOHN E. O'NEILL.
